NOTEBOOK

Eleanor Neas, Wantagh, N. Y.

Application March 5, 1957, Serial No. 644,096

2 Claims. (Cl. 150—28)

This invention relates to a notebook and more particularly to a notebook in combination with a woman's handbag or purse.

It is an objective of this invention to provide a notebook-handbag combination.

It is a further objective to provide a handbag having a swingable platform having a hard flat surface.

It is another objective to provide a notebook-handbag combination of simplified construction and inexpensive manufacture.

These and other objectives of this invention will become apparent upon reading the following description of a plurality of illustrative embodiments shown in the accompanying drawing in which;

Fig. 1 is a top view of the handbag-notebook combination,

Fig. 2 is an open view of the handbag-notebook combination open to show the construction of the rigid platform flat writing surface.

Fig. 3 is a cross-section view taken on line 3—3 of Fig. 2,

Fig. 4 is a section view of an edge similar to Fig. 3 but showing a modified means for securing the rigid platform in place and

Fig. 5 is a perspective view of a notebook-purse having opposed swingable platforms, disposed one each side of a centrally located purse.

A lady, and particularly a woman student, has need for taking notes or writing letters while away from home. To carry a pad of paper in a handbag is very inconvenient because of the bulk of the paper and besides a pad of paper does not have a sufficiently rigid back to write upon in the absence of a supplemental backing of the pad.

According to this invention, the notebook platform is very rigid and will permit writing even when the notebook is rested upon the writer's lap or knees. Thus, for example, travelers in aeroplanes can write letters while seated.

Moreover, where a female student uses this notebook-handbag combination she dispenses with the need for carrying a separate notebook for class room notes and thereby avoids the possibility of losing valuable lecture notes.

Other advantages to the user of this notebook-handbag combination are present, for example, the combination may be made in the size of a small evening purse with a single rigid swingable platform having paper thereon for the taking of phone numbers, addresses, etc. during the course of a conversation.

Turning now to the drawing, a plastic conventional handbag 10 is provided with a conventional carry strap 11 secured as by heat fusion, and a "zipper" 12 for closing the handbag aperture.

The handbag of this invention is further provided with a swingable rigid platform secured to the conventional handbag. The securing of the swingable platform to the handbag compartment may be integral with a side wall of the handbag or the platform may be a separate unit

2

secured, for example, by sewing, adhesive, or other conventional means to the handbag compartment.

As shown in Figs. 1 and 2, the notebook-handbag combination may be made from a flexible unitary sheet of plastic provided with an aperture to receive the pocket-book "zipper" 12. The unitary sheet of plastic may be prepared from several separate flexible plastic sheets fused together by conventional fusion procedures. Preferably the swingable or hinged platform is integral with the adjacent side wall of the conventional handbag, so that the hinge line is in the flexible plastic sheet and disposed at the bottom edge of the handbag, thereby in effect forming a double side wall to the handbag, the outer wall 13 of which is integral to the inner wall 14.

15 As shown in Figs. 1 and 2, the outer wall 13 is provided with a turned inwardly rim 15 about the three exposed edges of wall 13. The flexible plastic used for the walls 13 and 14 may be any suitable pliable and flexible material, for example, polyethylene plastic. A rigid or substantially rigid platform 16 of plastic, leather, plywood, metal, glass, linoleum and the like material is disposed within the three turned over rims 15 of the exposed three edges of the outer wall 13.

20 Preferably, but optionally, a suitable longitudinal plastic strip 17 is fused at the hinge line 18 of the integral sheet forming inner wall 14 and outer wall 13. The strip 17 is fused also at its ends to the respective opposed edges of the rims 15 at a fusion line 19, preferably fused in an invisible manner to form invisible fusion lines.

25 30 Where a strip 17 is used, a four sided pocket or channeled rectangular rim is formed. The platform 16 is disposed in this pocket (Figs. 1 and 2) and preferably, but optionally, secured immovably therein by stitching where the nature of the platform material permits stitching as in the case of semi-rigid leather or linoleum.

35 A conventional "zipper" 21 is secured by conventional means such as adhesive or stitching about the exposed edges of walls 13 and 14 thereby permitting closing of the notebook compartment from its open position (Fig. 40 2) to its closed position Fig. 1.

In lieu of a turned over rim 15 the platform 16 may be captively held in place adjacent the inner surface of outer wall 13 by means of a separate rectangular strip 22 having a rectangular aperture 23 therein (Fig. 4).

45 40 Where a separate cover strip 22 having a suitably large aperture 23 is used, the edges of the strip 22 may be fused or sewn to all the edges of the outer wall 13X including the hinge line edge. Where the strip 22 is secured to the wall 13X by threads or stitches 24, the "zipper" 21 may be simultaneously secured by said stitches 24.

55 Turning now to Fig. 5, there is shown an embodiment made from two parts, namely a purse 25 and a double platform 26. The purse 25 is made of flexible plastic and may be closed by a "zipper" or by pressure seizure knobs 27. The base of the purse 25 is provided with a substantially flat base wall 28 having preferably but optionally longitudinal opposed integral flanges 29.

60 The double platform part 26 of the notebook-purse combination is preferably a molded one piece flexible plastic structure having opposed inwardly directed U-shaped channels 30. A platform channel 30 is thus provided in each wall section forming the outer walls of the notebook-purse combination. The channel 30 of one outer wall is suitably spaced apart from the channel 30 in the opposed outer wall of the platform 26 to permit the base 28 of purse 25 to be secured therebetween and to the median line area of side platform 26. The securing of the purse 25 to the double platform 26 is by conventional means and preferably is by fusion or adhesive.

65 70 As shown in Fig. 5, the channels 30 are each provided with a pair of cut-outs 31 disposed respectively adjacent

to the base 28 of the purse 25. A pair of conventional co-acting snap-buttons 32 may be used to removably secure an outer platform wall to the purse 25 side, or a conventional non-toothed plastic slide fastener 33 may be used.

The separate platforms of the double platform part of the notebook purse combination of Fig. 5 form a pair of opposed double outer walls of the purse when the notebook platforms are closed. Clearly each platform wall is separately or independently opened. A rigid platform element 34 is inserted into the channel 30 of a wall and held therein by pressure fit to the channel inner surfaces. To insert a platform 34 into the wall the purse 25 is moved to the left (Fig. 5) in the direction of the arrow until the plane of the adjacent purse side wall 34X is in substantial continuous planar relationship to the plane of the inner surface of the adjacent platform wall. This exposes the edges of the cut-outs 31 in a manner permitting the rigid platform 34 to be slipped into place in the channel 30.

Optionally a pad of suitably perforated paper 35, with or without a rigid back, may be inserted into a channel 30 and held therein by pressure fit and seizure of the channel 30 walls to the paper. Where multiple sheets are used in the form of a pad, the sheets themselves present a rigid platform. The perforations 36 of the pad 35 are disposed exterior of the channel 30 along the three exposed edges of the outer platform wall, thereby facilitating tearing out of a sheet of paper after a written message has been entered thereon.

This invention has been illustrated and described by

means of a plurality of embodiments but clearly it is broader than these illustrations. Clearly such innovations as a sewn pocket 37 (Fig. 2) for holding stationery and pockets 38 for pencils and rulers are optionally added, if desired.

I claim:

1. A two-piece notebook-purse combination comprising a purse element having a substantially flat base; a double platform element secured at its median area to said base of said purse element, said double platform element having opposed platforms each having a U-shaped channel, each of said channels having a pair of cut-outs at their respective ends to facilitate insertion of a flat rigid element.

2. The combination of claim 1 comprising a rigid platform disposed in pressure fit relationship in one platform wall and a pad of suitably perforated paper in the other platform wall.
